FOOT ADJUSTMENT FOR CABINETS

Bernard Schramka, Chicago, Ill., assignor to
De Vry Corporation, Chicago, Ill., a corporation
of Illinois

Application December 7, 1945, Serial No. 633,499

2 Claims. (Cl. 45—139)

1

This invention relates to certain new and useful improvements in foot adjustment for cabinets.

The invention is particularly adaptable for use in connection with motion picture projecting machines where it is desirable, for properly locating a picture upon a screen to have the front portion of the cabinet of the machine elevated at the proper angle with respect to the horizontal. The apparatus for this purpose must be capable of being operated in a simple and expeditious manner in order to properly adjust the cabinet with respect to the horizontal, and such adjustment should be accomplished by the employment of one hand, thus enabling the operator to firmly hold the cabinet in place by the use of his other hand while making the adjustment.

As a principal object of this invention, it is sought to provide a mechanism which will accomplish the function of permitting expeditious and convenient adjustment of the foot so as to elevate one portion of the cabinet, and which will function to maintain the cabinet with its end portion elevated by virtue of the weight of the cabinet imposed upon the mechanism, all by means of an arrangement of parts which are simple, capable of easy assembly, and which will work in a most efficient and expeditious manner.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a side elevational view of a cabinet showing my improved foot adjustment associated therewith;

Fig. 2 is an elevational view of the foot adjustment embodied in my invention;

Fig. 3 is a fragmentary rear elevational view of the same;

Fig. 4 is a fragmentary sectional detail view taken substantially on line 4—4 of Fig. 3.

The drawings illustrate the preferred form of construction by which the several objects of my invention are accomplished.

In this connection a cabinet is indicated at 10, and this cabinet may be of any approved style and construction, but for purposes of illustration I describe the cabinet as containing a motion picture projecting apparatus. The cabinet 10, at its rear portion 11, has secured on opposite sides thereof feet 12. The front portion 13 of the cabinet is supported by the adjustable foot 14 which constitutes the subject matter of my improvements.

2

This adjustable foot 14 comprises a mounting plate 15 secured to a cabinet portion 16 by means of suitable screws 16. This mounting plate 15 has a recessed portion 17, and positioned in this recessed portion 17 are the mounting flanges 18 of a brake housing 19, the flanges 18 being secured to the mounting plate 15 by suitable screws 20. The housing 19 has a unitary partition 21 which divides the housing into a rear compartment 22 and a forward compartment 23.

A coupling is indicated at C, and this coupling comprises a shaft 24, rotatably carried by the housing 19, and having thereon a pinion 25, the portions 26 of which are utilized to pin a release disc 27 on the shaft 24. The cylindrical wall 28 of the housing 19 is provided with vertical openings 29 through which projects a rack bar 30, the teeth 31 of which mesh with the teeth 32 of the pinion 25. The lower end portion 36 of this rack bar 30 is connected as at 37 to a transverse bar 38, the opposite ends of which carry feet 39 similar to the feet 12.

The disc 27 provides a shoulder 40, and adapted to engage this shoulder 40 is an inturned lug 41 formed as an integral part of a release plate 42. This release plate 42 is formed as a part of the sleeve 43 of the coupling and telescopically receives the end 44 of the shaft 24. Pinned as at 45 to this stud shaft 44 is a hand wheel 46.

30 The release plate 42 opposite the lug 41 provides a second lug 47 which engages in a hook-shaped portion 48 formed in one end portion 49 of a brake band 50. This brake band 50 is adapted to have braking engagement with the brake lining 51 mounted against the cylindrical wall 52 of the housing 19. The opposite end portion 53 of the brake band 50 is secured as at 54 to the disc 27.

This brake band 50 is preferably formed of an elongated flat piece of spring material, and the arrangement is such that the weight of the cabinet transmitted to the shaft 24 will have a tendency to urge rotation of the shaft 24 in an anticlockwise direction as viewed in Fig. 3, but due to the fact that when the shaft 24 is rotated in this direction, the rotation therewith of the disc 27 will tend to bear the brake band against the brake lining, with the result that a braking effect will be brought about between the shaft 24 and the housing 19, and consequently 45 maintain the cabinet 10 from moving down from its tilted position such as shown in Fig. 1. To elevate the forward portion 13 of the cabinet 10, the shaft 24 is rotated in a clockwise direction as viewed in Fig. 3. This is accomplished by 50 rotating the handle 46 in that direction, which rotation of the handle in turn rotates the cou-

pling sleeve 43 so as to bear the lug 41 against the shoulder 40, thus imparting rotation to the disc 27, which disc when rotated in a clockwise direction as viewed in Fig. 3, will tend to drag the end portion 53 of the brake band therewith and relieve the braking pressure of the brake band upon the brake lining. To lower the front end 13 of the cabinet 10, the handle is rotated in an anticlockwise direction as viewed in Fig. 3. This will rotate the lug 47 in bearing engagement with the hook-shaped portion 48 and thus relieve the pressure of the brake band against the brake lining. By this arrangement the cabinet is maintained in an elevated position against its own weight, so that it cannot suddenly drop from an elevated position to a horizontal position. The arrangement affords easy operation of the mechanism to raise or lower the cabinet, and in this operation of raising or lowering the cabinet it requires but the use of one hand of the operator.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A foot for a cabinet or the like comprising a mounting member adapted for connection to a wall of the cabinet, a brake housing secured to said member, a brake band in said housing and adapted for braking engagement with a wall thereof, means arranged in the housing for contracting said brake band from braking engagement with said housing wall, a foot, and rack and pinion connection between said foot and an element of said contracting means, said contracting means comprising a coupling rotatably car-

ried by the housing and said coupling comprising a shaft and a coupling sleeve, a release disc on the shaft and arranged in the housing and provided with a shoulder in the path of rotation of said coupling sleeve in one direction, means connecting one end portion of the brake band to said disc, the opposite end portion of said brake band having a hook formation, and means on said sleeve for alternately engaging said shoulder and said hook formation.

2. A foot for a cabinet or the like comprising a member adapted for connection to a wall of the cabinet and having an opening formed therein, a brake housing secured to said member, a shaft rotatably mounted in said housing, a foot, rack and pinion connection between said foot and said shaft, a brake band in said housing and adapted for braking engagement with a wall thereof, means providing connection between one end of said brake band and said shaft including a shoulder, a stud shaft projecting through said opening and having independent rotation relative to said shaft and having means adapted to engage said shoulder to rotate said shaft in a direction to relieve the pressure of said brake band against said wall of said housing, means providing a connection between said stud shaft and the opposite end of said brake band to relieve the pressure of said brake band against said wall of said housing when said stud shaft is rotated in an opposite direction, and a handle on said stud shaft for rotating the latter.
